(57) **CLAIM**

The ornamental design for an electronic display mounted to a wall, as shown and described.

DESCRIPTION

FIG. 1 is a front isometric view of an electronic display mounted to a wall.

FIG. 2 is a rear isometric view of the electronic display and wall of FIG. 1.

FIG. 3 is a front view of the electronic display and wall of FIG. 1.

FIG. 4 is a right side view of the electronic display and wall of FIG. 1.

FIG. 5 is a rear view of the electronic display and wall of FIG. 1.

FIG. 6 is a left side view of the electronic display and wall of FIG. 1.

FIG. 7 is a top view of the electronic display and wall of FIG. 1.

FIG. 8 is a bottom view of the electronic display and wall of FIG. 1; and,

FIG. 9 is a partial cross-sectional view of the electronic display taken along line 9-9 of FIG. 1.

The broken lines form no part of the claimed design. The internal features of the electronic display form no part of the claimed design.

1 Claim, 5 Drawing Sheets
